CLAIM

The ornamental design for a fluorescent basketball goal assembly, as shown and described.

DESCRIPTION

FIG. 1 is a front elevational view of the fluorescent basketball goal assembly of the present invention;

FIG. 2 is a rear elevational view of the fluorescent basketball goal assembly of FIG. 1;

FIG. 3 is a left side elevational view of the fluorescent basketball goal assembly of FIG. 1, the right view being a mirror image thereof;

FIG. 4 is a top plan view of the fluorescent basketball goal assembly of FIG. 1; and,

FIG. 5 is a bottom plan view of the fluorescent basketball goal assembly of FIG. 1.

1 Claim, 4 Drawing Sheets
